UNITED STATES PATENT OFFICE.

FRANZ WINDHAUSEN, OF BERLIN, GERMANY.

VARIABLE-SPEED MULTIPLE-STAGE TURBINE.

No. 806,720.

Specification of Letters Patent.

Patented Dec. 5, 1905.

Application filed February 16, 1905. Serial No. 245,949.

To all whom it may concern:

Be it known that I, FRANZ WINDHAUSEN, engineer, of 1 Corneliusstrasse, Berlin, Germany, have invented certain new and useful 5 Improvements in Improved Variable-Speed Multiple-Stage Turbines, of which the following is a clear and perfect description.

The present invention relates to multiple-stage steam or gas turbines which are adapted 10 to run at more than one speed.

Steam-turbines in which the drop in the steam-pressure, the number of stages, and the angle of discharge for the steam are constant give good results as far as the consumption of 15 steam is concerned only when the machine runs at a definite speed. The following proposals have been made in order to obtain economy in steam consumption in the case of a steam-turbine running at various speeds:

20 First, in the case of multiple-stage steam-turbines to vary the number of the stages by removing the guiding devices of one or more stages from the course of the steam by means of special devices; second, in the case of 25 single-stage steam-turbines (in the case of which the number of stages is invariable) to provide two or more groups of nozzles having separate means for the admission of steam, the angles of discharge of which groups of 30 nozzles are of different magnitudes and to supply steam to the one or to the other group of nozzles according to the speed desired; third, in the case of multiple-stage steam-turbines to vary the angle of discharge of the 35 steam in the first stage and simultaneously to also alter the number of stages of the turbine. In the case of these turbines two or more groups of nozzles provided with separate means for steam admission are employed in the 40 first stage, the angles of discharge of said groups of nozzles being different, whereas in the following stages the angles of discharge of the guiding devices are constant, while the number of stages can be altered by switching 45 out one or more stages.

The present invention relates to a multiple-stage steam or gas turbine the speed of which can be altered.

One feature of a turbine constructed according to the present invention is that in its individual stages two or more coöperating groups of guiding devices are arranged which may have separate steam admission and in which the admission-angle or the discharge- 55 angle or both angles of the first stage and

also of the following stages of the one group are different from the corresponding angles of the guiding devices of the other group or groups. For each velocity desired it is advantageous to have a group of guiding devices, the angle of admission and the angle of discharge of which are adapted to the desired velocity. Each separate group of guiding devices may have separate means for the admission of live steam. If, for example, a multiple-stage turbine is to be adapted to run at two different speeds, in each stage of the turbine two guiding devices may be arranged, which form in the turbine two coöperating groups. The admission-angle or the discharge-angle or both angles of the guiding devices of the one group for the one velocity are different from the corresponding angles of the guiding devices of the other group for the other velocity. 75

Two embodiments of the present invention are illustrated in the accompanying drawings, in which—

Figure 1 is a diagrammatic longitudinal section of a multiple-stage actual steam-turbine, 80 the turbine being adapted to run at two different speeds. Fig. 2 is a diagrammatic transverse section on the line A B of Fig. 1. Fig. 3 is a diagrammatic development of a part of the vane-wheels and guiding devices. 85 Fig. 4 is a diagrammatic transverse section, and Fig. 5 a diagrammatic longitudinal section of a second embodiment of the present invention.

Referring to the embodiment shown in 90 Figs. 1, 2, and 3, it will be seen that the turbine has only one chamber. Two groups of guiding devices b' to b^5 and c' to c^5 , respectively, corresponding to the two different speeds required, are provided in the turbine. In each 95 stage one guiding device of each group b' to b^5 and c' to c^5 is arranged. Steam is admitted to the group b' to b^5 , as indicated by the arrow 1, and to the group c' to c^5 , as indicated by the arrow 2. The admission-angle and discharge-angle of the guiding devices b' to b^5 of the one group (in the present case each about twenty-three degrees) are different 100 from the corresponding angles of the guiding devices c' to c^5 of the other group (in the present case each about thirty degrees.) If now the turbine is to run, for example, at the lower speed, steam is admitted, as indicated by the arrow 1, only to the group c' to c^5 , which possesses the greater admission and discharge 110

angles, whereas for the higher speed steam is admitted, as indicated by the arrow 2, solely to the group b' to b^6 , which has smaller angles.

5 The above-described turbine contains only a single chamber or cell, and the steam-pressure within the chamber may be nearly uniform. Consequently the steam, which, for example, flows through the guiding devices 10 of the group b' to b^6 , has no or only a slight tendency to escape through the gaps between the guiding devices and the vane-wheels and so to pass away through the guiding devices c' to c^6 or to flow away in the direction of the 15 arrows 3 and 4. In the case of turbines which consist of several chambers or cells the steam flowing away from the particular group of the first chamber in use at the time can flow not only into the corresponding group of 20 guiding devices in the next chamber, but also into the other groups of guiding devices not belonging to this group, which are not suited to the speed required. This disadvantage can, in the case of multiple-stage turbines for various 25 speeds, be removed as much as possible by providing closing devices between the guiding devices of one chamber and those of the next chamber, of which closing devices only those are at the same time opened which 30 belong to one and the same group of guiding devices, whereas the closing devices for the remaining groups of guiding devices are closed. In Figs. 4 and 5 an example of such a turbine with two chambers g h is diagrammatically represented. This turbine with partial 35 radial flow is designed for two different speeds and accordingly possesses two groups of guiding devices b' to b^6 and c' to c^6 , respectively. The guiding devices b' to b^6 have steam 40 admission or discharge angles which are different from the corresponding angles of the guiding devices c' to c^6 . The group c' to c^6 serves, on account of its greater discharge-angle, for the slow speed, while the group b' to b^6 , 45 with its smaller discharge-angles, is for the higher speed. Closing devices i and m , respectively, are inserted between the guiding devices b' to b^3 and c' to c^3 , respectively, of the one chamber and the guiding devices b^4 to b^6 and c^4 50 to c^6 of the next chamber. Only those closing devices belonging to one group of guiding devices are entirely or partially opened at the same time, the other closing devices which belong to the other group being closed while the 55 former are opened. If, for example, the turbine is to run at the low speed, the live-steam valves f , as well as the closing devices i between the two chambers, are entirely or partially opened, and the steam can flow only 60 through the group of guiding devices c' to c^6 , while the live-steam valves l and the closing devices m for the group b' to b^6 are closed. By arranging closing devices between the guiding devices of one chamber and those of the next chamber it is rendered possible for the 65

steam flowing out of the last row of blades a^3 to be able to flow farther only through the opened closing devices i and the guiding devices c^4 to c^6 belonging thereto, because the closing devices m for the other group of guiding devices b^4 to b^6 are closed. If these closing devices i and m , respectively, were not provided, the steam passing away from the last row of blades c^3 would be able to flow both through the guiding devices c^4 c^5 c^6 and also 75 through guiding devices b^4 b^5 b^6 .

In the turbine represented in Figs. 4 and 5 each separate nozzle is provided with a separate closing device, (valve, cock, slide, or the like,) in order that the quantity of steam flowing therethrough may be regulated in a well-known manner according to the power required. In many cases it is sufficient to arrange only a single closing device between the guiding devices of the one chamber and the corresponding guiding devices of the next chamber.

In the case of turbines having very many pressure-stages it is not always necessary for the guiding devices of each pressure stage or chamber to be provided with closing devices. In many cases it is sufficient for only some of the chambers to be provided with closing devices.

In the case of turbines according to the present invention, the features of which have been described above, it is indeed advantageous, but not always necessary, for a guiding device to be provided in each stage for each of the various desired speeds. In many cases it is sufficient for two or more groups of guiding devices to be arranged only in some, but not in all of the stages of the turbine.

What I claim as my invention, and desire to secure by Letters Patent, is—

1. A multiple-stage steam-turbine for various speeds comprising two or more groups of guiding devices for each stage and to each set of which groups steam can be separately admitted, the discharge-angle of the guiding devices of the first set being different from the corresponding angle of the guiding devices for the other set or sets.

2. A multiple-stage steam-turbine for various speeds comprising two or more groups of guiding devices for each stage and to each set of which groups steam can be separately admitted, the discharge-angle of the guiding devices of the first set being different from the corresponding angle of the guiding devices for the other set or sets, and the admission-angle of the intermediate guiding devices of one set being different from the corresponding angles of the guiding devices of the other set or sets.

3. A multiple-stage steam-turbine for various speeds comprising two or more groups of guiding devices for each stage and to each set of which groups steam can be separately admitted, the admission-angle of the intermediate

diate guiding devices of one set being different from the corresponding angles of the guiding devices of the other set or sets.

4. A multiple-stage steam-turbine for various speeds comprising a plurality of chambers, two or more groups of guiding devices arranged in each of said chambers and to each set of which group steam can be separately admitted, the discharge-angle of the guiding devices of one set being different from the corresponding angles of the guiding devices of the other set or sets, and closing devices interposed between the guiding devices of one chamber and those of the next chamber, the closing devices of one set of guiding devices alternately operating with respect to the closing devices for the other set or sets of guiding devices.

5. A multiple-stage steam-turbine for various speeds comprising a plurality of chambers,

two or more groups of guiding devices arranged in each of said chambers and to each set of which groups steam can be separately admitted, the admission-angle and the discharge-angle of the guiding devices of one of the sets being different from the corresponding angles of the other set or sets, and closing devices interposed between the guiding devices of one chamber and those of the adjacent chamber, the closing devices for the guiding devices of one of the sets alternately operating with respect to the closing devices of the other set or sets.

In testimony whereof I have hereunto set my hand in presence of two subscribing witnesses.

FRANZ WINDHAUSEN.
